MULTIPLE PURPOSE NOZZLE

Oliver L. Allen, Riverside, Conn., assignor to Electrolux Corporation, Old Greenwich, Conn., a corporation of Delaware

Application August 20, 1954, Serial No. 451,174

2 Claims. (Cl. 15—417)

My invention relates to cleaning tools for vacuum cleaners and more particularly to a tool of this type which includes two different suction nozzles designed to clean different types of surfaces.

As is disclosed in Patent No. 1,849,515 issued July 16, 1930 to Lars Ell, it has been known to provide two different types of nozzles on a member which is pivotally mounted on a suction conduit so that either nozzle may be brought into operative position by rotating the member 180° around the conduit, such rotation at the same time shifting a valve so as to connect the proper nozzle to the source of suction. However, such an arrangement imposes a limitation on the minimum height of the tool, inasmuch as such height must be somewhat greater than the diameter of the smallest suction conduit which is capable of transmitting the desired air flow. Especially in a combination tool for use on the floor, it is advantageous to have the overall height of the tool as small as possible in order that it may be used under low furniture and it is one of the objects of my invention to provide a combination rug nozzle and floor brush having such minimum height.

In accordance with my invention this is accomplished by using a suction conduit having a noncircular cross-section with the minor axis thereof extending in a vertical direction. This of course makes it impossible to have the cleaning tool rotatably mounted on the suction conduit, and in order to turn the tool over this conduit is rotatably connected to another suction conduit, preferably in the form of an elbow, and the suction conduit is slidable with respect to the tool so as to provide a valve arrangement for connecting the proper nozzle to the source of suction.

Further objects and advantages of my invention will be apparent from the following description considered in connection with the accompanying drawings which form a part of this application and of which:

Fig. 1 is a cross-sectional view of one embodiment of my invention with the rug nozzle in operative position and is taken on the line 1—1 of Fig. 2;

Fig. 2 is a cross-sectional view taken on the line 2—2 of Fig. 1;

Fig. 3 is a cross-sectional view similar to Fig. 1, but with the cleaning tool reversed so that the floor brush is in operative position;

Fig. 4 is a cross-sectional view similar to Fig. 3, but showing another embodiment of my invention;

Fig. 5 is a cross-sectional view similar to Fig. 3, but showing a still further embodiment;

Fig. 6 is a cross-sectional view on an enlarged scale taken on the line 6—6 of Fig. 5; and

Fig. 7 is a view similar to a portion of Fig. 6, but showing certain parts in a different position.

Referring more particularly to Figs. 1 through 3, reference character 10 designates the body member of a suction cleaning tool having a suction throat 12 of a rug nozzle on one face thereof and a suction throat 14 of a floor brush on the opposite face. The rug nozzle in-

2

cludes a forward lip 16 and a rear lip 18 and end lips 20 of suitable configuration to contact a soft floor covering, such as a rug or carpet. The floor brush includes rows of bristles 22 which bound the throat 14 and are suitable for cleaning a hardwood floor or any hard floor covering.

Extending into the body 10 from the rear face thereof is a passageway 24 having a rectangular cross-section, the minor dimension of which extends vertically. An opening 26 connects throat 12 with this passageway, while an opening 28 connects throat 14 with the passageway, the two openings being displaced with respect to each other lengthwise of the passageway.

A suction conduit 30 has its forward end formed as a hollow rectangular valve member 32 which is slidably mounted within the passageway 24. This valve member is formed with aligned ports 34 and 36 adapted to cooperate with the openings 26 and 28, respectively, in the body 10.

One of the surfaces of the rectangular portion of suction conduit 30 is provided with a pair of notches 38 and 40 which are spaced apart a distance equal to the distance between the center lines of openings 26 and 28. Pivotally mounted on the rear face of the body 10 is a latch member 42 which, in the position shown in Figs. 1 and 2, engages one of the notches 40, but which may be pivoted in either direction so as to disengage the end thereof from the notch.

The opposite end of conduit 30 is cylindrical and there is rotatably mounted therein the cylindrical end of an elbow 44 which is arranged to receive the end of the usual suction wand connected to a source of suction in a vacuum cleaner.

With the parts in the position shown in Fig. 1, it will be seen that the rug nozzle including the throat 12 between the lips 16 and 18 is in communication with the interior of suction conduit 30 through the opening 26 and the port 34. Consequently, if suction is applied to the conduit 30 through the elbow 44, air will be caused to flow in the direction of the arrows and this air will pick up and remove dirt from the rug or other surface over which the nozzle is moved. If it is desired to use the tool under low furniture, the rigid wand connected to the elbow 44 may be lowered to a position parallel with the floor by rotating the elbow 90° with respect to the conduit 30, without in any manner interfering with the flow of air. It will be noted that the vertical height of the tool is only slightly greater than the diameter of the cylindrical part of the conduit 30 and is considerably less than would be the case if the nozzle body 10 were made thick enough to embrace a cylindrical conduit having such a diameter. However, by having the end of the conduit 30 which is received in the body 10 of rectangular shape, as particularly shown in Fig. 2, it is possible to have a minimum height of the body 10.

If it is desired to use the floor brush, the latch member 42 is pivoted in either direction sufficiently so as to disengage the end thereof from notch 40, and the suction conduit 30 is slid further into the passageway 24 until the port 36 is aligned with the opening 28. In this position, the latch may be pivoted back so that its end engages the notch 38, thus locking parts in this position. In order to bring the floor brush into contact with the floor, the body 10 and the conduit 30 may then be rotated 180° about the end of the elbow 44 so that the parts will occupy the position shown in Fig. 3. In this position it will be seen that the throat 14 of the floor brush is in communication with the suction conduit 30 through the opening 28 and the port 36 and consequently the air drawn in through this path will pick up dust from the surface over which the floor brush is passed.

The embodiment shown in Fig. 4 is similar to that shown in the preceding figures, with the exception that the openings 26a and 28a in the nozzle body are in alignment with each other, while the ports 34a and 36a in the valve portion 32 are spaced from each other in the direction of movement of the valve member. Thus, with the parts in the position shown in Fig. 4, the port 36a is aligned with the opening 28a, thus connecting the floor brush to the suction conduit. In order to connect the rug nozzle, the latch 42 is pivoted, and the suction conduit 30 pulled outwardly until the latch may engage the notch 40, whereupon the port 34a will be in alignment with the opening 26a to the rug nozzle.

In the embodiment illustrated in Figs. 5, 6 and 7, the nozzle body is made of two parts 10a and 10b which are joined together by one or more screws 50. The passageway 24 is formed entirely in the part 10b but is bounded on one side by a surface of the part 10a. A slot 52 is formed in this surface of part 10a immediately adjacent to the passageway 24 and a pin 54 extends from the valve member 32 and is slidable within the slot, thus limiting the displacement of the valve member in the passageway so that the suction conduit 30 may not be entirely withdrawn.

Member 10b is formed with a slot 56 extending in from the side of the passageway 24 and pivotally mounted therein is a lever 58 having an exterior handle portion 60. The inner end of the lever is formed as a hook 62 which extends around a pin 64 which is disposed vertically in one corner of the passageway 24 and serves as a fulcrum for the lever. A spring 66 is disposed in the slot 56 behind the lever and urges the latter against the side of the valve member 32. This lever carries a projection 68 which, in the position of the parts shown in Fig. 6, is received within a notch 70 formed in the side of the valve 32. If the lever is pivoted in the direction of the arrow in Fig. 6, the projection 68 is withdrawn from the notch 70, thus permitting the valve member 32 to be moved outwardly as far as is permitted by the pin 54 in the groove 52, that is to the position shown in Fig. 7, in which position the projection 68 abuts against a shoulder 72 formed on the valve member, thus holding it in this position. Incidentally, the cut-away portion of the valve member which forms the shoulder 72, also provides a space for receiving pin 64 when the valve member is in the position shown in Fig. 6.

The operation of this embodiment is the same as that previously described, with the exception that the valve member is released for movement by pressing against 50 the handle portion 60 of the lever 58, instead of by pivoting the latch member 42. An advantage of this embodiment is that the spring 66 automatically reengages the projection 68 with the valve member as soon as the latter reaches either of its terminal positions, hence making it unnecessary for the operator to do this.

While I have shown several more or less specific em-

5 bodiments of my invention, it is to be understood that this has been done for the purpose of illustration only and that the scope of my invention is not to be limited thereby, but is to be determined from the appended claims.

What I claim is:

1. In a suction cleaning tool, a relatively rigid body member, dissimilar suction nozzles formed on opposite faces of said member, a passageway extending into said body member between said faces and having a rectangular cross-section with the minor dimension thereof disposed normal to said faces, a valve member having a corresponding rectangular cross-section slidably mounted in said passageway for in and out movement and formed with valve ports in the opposite wider sides towards the respective faces, said body member being formed with an opening from each suction nozzle to said passageway, said openings and valve ports being arranged with respect to each other so that when one port is aligned with the cooperating opening the other port is out of alignment with the other opening, latching means for securing the valve selectively in operative position with either suction nozzle and a suction conduit connection member rotatably mounted on said valve member in fluid communication with the interior thereof, the vertical distance between the exterior faces of said body member being of a minimal height commensurate with the vertical height at the attached conduit member in order to introduce the tool into narrow openings, such as beneath furniture or cabinets.
2. In a suction cleaning tool, a body member, dissimilar suction nozzles formed on opposite faces of said member, a passageway extending into said body member between said faces and having a rectangular cross-section with the minor dimension thereof disposed normal to said faces, a valve member having a corresponding rectangular cross-section slidably mounted in said passageway for in and out movement and formed with valve ports in different sides thereof, said body member being formed with an opening from each suction nozzle to said passageway, said openings and ports being arranged with respect to each other so that when one port is aligned with the cooperating opening the other port is out of alignment with the other opening, and latching means for securing said valve against sliding movement in operative relation with either nozzle.
